UNITED STATES PATENT OFFICE

IRVING R. HIPPMAYER, OF WAUKESHA, WISCONSIN, ASSIGNOR TO THE CREAMERY PACKAGE MFG. COMPANY, OF CHICAGO, ILLINOIS, A CORPORATION OF ILLINOIS

UNLOADING MECHANISM FOR CAN WASHING MACHINES

Application filed July 5, 1929. Serial No. 376,255.

The invention relates to milk can washing machines of the type in which the cans are conveyed through a succession of zones wherein they are subjected to cleansing treatment, and more particularly relates to mechanism for unloading the cans from the conveyor after having received the treatment.

In the machine herein disclosed, an endless conveyor is employed to carry the cans through a circuitous arrangement of cleansing zones wherein various treating devices operate upon the succession of cans, as further disclosed in my copending applications bearing Serial Numbers 376,254 and 376,256, filed July 5th, 1929, after which the cans are automatically ejected and righted and their covers placed thereupon.

The principal object of the invention is to provide automatic mechanism of improved construction for receiving and righting the cans as they are ejected from the conveyor, and for receiving the covers and placing them upon their respective cans.

Another object is to provide means for delivering the righted cans to a conveyor for movement of the cans to storage.

A further object is to provide mechanism for arresting the cans, after being righted, in position to receive their respective covers.

Other objects and advantages will be apparent in the following detailed description of a preferred embodiment of the invention which I have selected for illustration in the accompanying drawings. It will be understood, however, that various changes in form, construction and arrangement may be made by those skilled in the art, without departing from the spirit and scope of the invention, as expressed in the appended claims.

Referring to the drawings, Fig. 1 represents a side view of a portion of the washing machine with which the unloading mechanism is incorporated. Fig. 2 is a cross sectional view in elevation of the portion of the machine related to the unloading mechanism. Fig. 3 is a plan view of the can righting, delivering and positioning mechanisms, and Fig. 4 is a sectional side elevation of the same. Fig. 5 is a sectional side elevation of a portion

of the can cover receiving device and associated parts of the machine cover conveyor.

First describing in general the washing machine mechanism with which the unloading mechanism is associated, the reference numeral 1 indicates a vertically positioned drive shaft having its bearings in brackets 2 and 3 supported upon the partition walls 4 of the machine. The drive shaft 1 is rotated intermittently by means of a conventional Geneva stop mechanism comprising a star wheel 5 and a driver 6 of which the driver is mounted on a shaft 7 having its bearings in the bracket 3 and in the machine base 8.

A bevel gear 9, mounted on the shaft 7, is in driven mesh with a bevel pinion 10 mounted on a shaft 11 carrying a gear 12 of a conventional worm and gear drive of which the worm shaft 13 carries a pulley 14 belted in conventional manner to the drive pulley of an electric motor 15.

Secured on the shaft 1 is an upper sprocket 16 and a lower sprocket 17 which extend through openings in the partition walls 4 and respectively support, at one end of their operative runs, a pair of chain or link belts 18 and 19 extending longitudinally of the machine. The opposite ends of the belt runs are supported upon a similarly positioned pair of idler sprockets and shaft (not shown).

Regularly spaced along and secured to the belts 18 and 19 is a series of can holders, each comprising a pair of horizontally positioned laterally open U shaped straps 20 providing lateral support for a can 21 standing within them, the outer ends of the upper and lower straps preferably being connected as by upright straps 22. A bottom grid plate 23 supports the weight of the can inverted thereupon with its open mouth portion resting upon the open grid through which the cleansing fluids are introduced into the can. The side straps 20 are rearwardly fixed upon an upright bar 24 which is attached at its upper and lower ends respectively to upper and lower roller brackets 25 and 26, the latter being secured to appropriately formed links in the chain belts 18 and 19.

Each of the brackets 25 and 26 is provided

with a pair of rollers 27, the rollers of the upper brackets operatively bearing upon a stationary rail 28, and those of the lower brackets bearing upon another stationary rail 29.

5 The rails 28 and 29 are positioned respectively below and parallel to the belts 18 and 19 throughout their paths of travel, and are suitably mounted upon the adjacent walls of the machine. The rails 28 and 29 support 10 the weight and guide the movement of the can holders and their contents, while the belts 18 and 19 serve as operating and spacing means for the holders.

15 The grid plate 23 of each holder is rearwardly supported by horizontal pivotal attachment, as at 30, to the lower bracket 26, and is frontwardly supported by rollers 31 pivoted thereon and bearing upon a stationary rail 32 positioned outwardly of and parallel to the path of the bracket 26, and having suitable support on the frame of the machine. The rail 32 serves to maintain the pivoted grid plate 23 in horizontal position 20 throughout their travel, except at the point where the cans are discharged from the holders after the cleansing treatment is completed. As illustrated at 33, a portion of the rail is lowered a substantial distance below 25 the normal horizontal plane of the rail. As the can holders reach this lowered portion of the rail, the rollers 31 pass downward and lower the outer end of the plate 23, thus outwardly tipping a can supported on the plate 30 to an angle causing it to fall clear of the conveyor.

Rigidly mounted on the upper end of the bar 24, in each of the can holders, is an L-shaped bracket 34 extending laterally outward in the form of spaced arms 35. Pivotally supported between the arms 35 is a 40 can cover carrier 36 comprising a pair of spaced U shaped plates rearwardly secured to suitable spacer base, and adapted to receive and support a can cover 37 between 45 their outwardly extending arms.

A bell crank 38 is pivotally mounted upon the upper side of the bracket 34, one arm of the crank being pivotally connected to a link 50 39, the latter also being pivotally connected to the cover carrier 36 rearwardly of the carrier's pivotal support. The other arm of the bell crank 38 carries a roller 40 extending into operative contact with a stationary cam 55 rail 41 having suitable support on the frame of the machine, and positioned parallel to the path of movement of the bracket 34 except as to the portion 42 immediately over the lowered portion 33 of the rail 32, the cam 60 rail portion 42 being curved inwardly for a substantial distance. The cam rail actuates

the bell crank in control of the position of the cover carrier. The outer ends of the latter normally are uplifted to retain the cover 65 by gravity during the cleansing treatment,

and upon arrival at the point of discharge of the can, the carrier is lowered to horizontal position through the cam action of the portion 42 of the cam rail.

70 Pressure jet mechanisms, for applying cleansing fluid to the inner and outer surfaces of the successive cans carried on the conveyor, are indicated generally at A and B in Fig. 2, the same being described in detail and claimed in my copending application, Serial Number 376,256.

75 The unloading mechanism is incorporated with the washing machine at the position where the successive grid plates 23 are lowered and the cans are toppled therefrom as described above. A cross bar 43, suitably mounted on the machine frame, may be provided at the discharge position to engage the lower end of the can as it falls from the plate 23, thereby facilitating the turning 80 movement of the falling can.

85 Outwardly of the discharge position is a tiltable can chute 44 mounted in a suitable frame or cradle 45, the latter being secured at one end upon a shaft 46 having its bearings in a pair of spaced brackets 47 mounted on outer frame members 48 suitably attached to the machine structure. In can receiving position, the chute 44 is tilted angularly toward the discharge position of the can conveyor and rests upon a stop 49 mounted on the frame structure. The chute and supporting cradle are swingable into upright position by means of a crank lever 50 secured upon one end of the shaft 46, the crank 90 50 being pivotally connected to a link 51 which is pivotally connected to another crank lever 52 secured upon a shaft 53 having its bearings in suitable brackets 54 attached to the machine frame structure.

105 The shaft 53 is given a rocking movement by a crank lever 55 secured thereto and endwardly carrying a roller 56 having operative contact with a cam 57 mounted on a rotating shaft 58 having bearing support in brackets 59 mounted on the base structure of the machine. The shaft 58 is rotated by a bevel gear 60 secured thereon and having driven engagement with a pinion 61 mounted on the worm gear shaft 11. The operating train 110 for the chute 44 is timed to lower the chute into inclined can receiving position in advance of the movement by the conveyor of the successive can holders to the position of discharge.

115 As each grid plate 23 reaches the lowered portion 33 of its supporting rail, the can resting thereon is toppled into the chute 44 and slides downward in the chute into abutment with the inwardly hooked ends of a pair of pivoted stop bars 62.

120 The latter are pivotally supported, as at 63, upon suitable brackets mounted on the frame structure, and endwardly carry laterally extending eye bolts 64 passing freely through 125

130

5 a pair of stationary bars 65 secured to the frame structure. Adjustable nuts 66 on the bolts 64 limit the inward movement of the bars 62, and compression springs 67 resiliently resist the outward movement of the bars 62.

10 On opposite sides of the chute 44, a pair of pins 68 are fixed in the pivoted cradle 45, each provided with a roller 69 having engagement with the respective bars 62 at inwardly inclined portions of the latter. As the chute and cradle are turned to upright position, the rollers 69 effect the lateral withdrawal of the bars 62 from support of the can within the chute, and release the can when fully righted. Thereafter, the chute is returned to lowered position to receive the next can.

15 20 When released from the chute, the can is dropped upon a short continuous belt conveyor 70 provided to move the can outwardly and deliver it upon some other conveyor (not shown) for disposal of the washed cans. The conveyor belt 70 is operatively supported 25 upon a pair of rollers 71 and 72 having their shaft bearings in the brackets 47. The roller 72 is preferably supported in adjustable bearings indicated at 73, and the conveyor belt is actuated by a drive chain belt 74 running 30 over a sprocket mounted on the shaft 58 and a sprocket on the shaft of the roller 72.

35 Mechanism is provided for momentarily restraining the outward movement of the can, and for positioning the can to receive its cover, as hereinafter described, comprising a pair of laterally swinging horizontal curved arms 75 positioned over the conveyor belt 70.

40 The arms 75 are secured upon a pair of vertical shafts 76 having bearings in suitable brackets mounted on the upright members 48 of the frame structure. A pair of oppositely extending lever arms 77, mounted respectively on the shafts 76, are operatively connected by a link 78 and effect the simultaneous swinging inward and outward of the arms 75. Another lever arm 79, secured to one of the shafts 76, is operatively connected by a link bar 80 to one arm of a bell crank 81, pivotally supported upon a suitable bracket 45 50 mounted on the machine frame, and of which the other arm is in operative contact with a cam 82 mounted on the shaft 58. A spring 83, attached to the lever arm 79 and to the machine frame, normally effects the closing inwardly of the arms 75 to hold a can righted upon the conveyor 70 in position to receive its cover. The cam 82 then operates the lever train to open the arms 75, permitting the can to be moved forward by the conveyor.

55 60 The cover replacing mechanism is mounted above the can righting mechanism, and comprises a pair of laterally spaced brackets 84, suitably secured to the machine frame structure, and having formed therein curved descending slots 85. A cover chute 86 is posi-

tioned between the brackets 84, and is an end-wardly open box-like structure having a pair of spaced rollers 87 mounted on each side which operatively engage within the respective slots 85, the rollers supporting the chute 70 for movement between the extremities of the slots. An extended upper portion 88 of the chute is positioned beneath the path of the cover carrier 36, when the chute is in uppermost position, and is provided with an end flange 89 extending laterally inward of a cover 37 positioned in the carrier. 75

Upon movement of the chute 87 outward and downward, as guided by the slots 85, the cover is withdrawn from the carrier 36 and passes through the chute, as the latter is inclined in lowermost position, dropping by gravity upon the mouth of the can held in position to receive it.

80 85 The reciprocatory movement of the cover chute is accomplished by means of a pair of links 90 pivotally attached to opposite sides of the chute and operatively connected to a pair of lever arms 91 secured to a shaft 92 having its bearings in a pair of spaced brackets 93 mounted on the frame structure. Also secured to the shaft 92 is a crank lever 94 with which is pivotally connected a link bar 95 extending downward and pivotally connected to a lever arm 96 secured upon the shaft 53. 95 By this operating arrangement, the cover chute is moved to uppermost position in advance of the arrival at unloading position of the successive carriers 36, and then is moved to withdraw the cover when a can is in position to receive it. 100

I claim as my invention:

1. In a can washing machine, a can unloading mechanism comprising a chute operable to receive a can in inclined position and to swing said can to upright position, an operatively mounted bar having a portion extending transversely of said chute to engage and retain said can therein, means operable by said chute for disengaging said bar from said can as said chute is swung into upright position, and a conveyor adapted to receive said can from said chute when disengaged from said bar. 105 110

2. In a can washing machine, a can unloading mechanism comprising a chute operable to receive a can in inclined position and to swing said can to upright position, a swingable bar having a portion normally positioned to engage and retain a can in said chute in inclined position, a member carried by said chute operable to engage said bar with the swinging of said chute to upright position and to swing said bar out of engagement with said can, and a conveyor adapted to receive said can from said chute when disengaged from said bar. 115 120

3. In a can washing machine, a can unloading mechanism comprising a chute operable to receive a can in inclined position and 130

- to swing said can to upright position, a stop for retaining said can in said chute when in inclined position and operable to release said can in upright position, a conveyor adapted to receive said can when released by said stop, a pair of swingable arms normally positioned across the path of travel of said can upon said conveyor and effective to arrest the movement of said can, means for placing a cover on said can during said arrest of movement, and means operatively associated with said cover placing means for swinging said arms free of the path of said can when said cover has been placed on said can.
5. In a can washing machine, an unloading chute operable to receive a can in inclined position and swing said can into upright position, a cover chute operatively supported for movement into substantially horizontal position to receive a can cover, and for movement into inclined position adjacent to said can in upright position whereat said cover is caused to slide into position upon said can, and means for moving said cover chute into inclined position when said can is swung into upright position.
10. In a can washing machine, an unloading chute operable to receive and right a can discharged from said machine, a pair of spaced supports having slide ways, a cover chute having operative support in said slide ways, said slideways being formed to guide said cover chute into substantially horizontal position to receive a can cover and into inclined position to permit said cover to slide from said cover chute, and operating means for said unloading chute and said cover chute operable to cause said cover chute to move into inclined position when said unloading chute is in can righting position.
15. In a can washing machine, a can cover conveyor, cover unloading and replacing mechanism comprising a pair of supports having slideways therein, a cover chute having operative support in said slideways, said slideways being formed and positioned to guide said chute into cover receiving position adjacent to said cover conveyor, and to guide said chute into inclined position for the discharge therefrom of a cover upon a can positioned to receive said cover, said cover chute having a portion adapted to engage a cover positioned in said conveyor and to withdraw said cover from said conveyor with the movement of said chute, and means for causing reciprocatory movement of said chute along said slideways.
20. In witness whereof I have hereunto attached my signature.
25. IRVING R. HIPPENMEYER.
